(57) CLAIM

I claim the ornamental design for vehicle wheel with spokes, as shown and described.

DESCRIPTION

FIG. 1 is a front elevation of the vehicle wheel according to one embodiment, showing my new ornamental design.

FIG. 2 is a side perspective view thereof, wherein the sides of the wheel are shown in broken lines for illustrative purposes only.

FIG. 3 is a front elevation of the vehicle wheel according to another embodiment, showing my new ornamental design; and,

Any letters, numerals or other indicia shown are by way of illustration, and do not form part of the claimed design. Shading does not form part of the claimed design, except for purposes of indicating physical contours. The side and rear views of the wheels of each of the embodiments of FIGS. 1, 2, and of FIGS. 3, 4, do not comprise part of the claimed subject matter. The color and surface finish do not comprise part of the claimed design.

The broken line showing of environment is for illustrative purposes only and forms no part of the claimed design.
